UNITED STATES PATENT OFFICE

135,530

DESIGN FOR A HANDBAG

Daniel Rubin, New York, N. Y.

Application March 22, 1943, Serial No. 109,791

Term of patent 3½ years

To all whom it may concern:

Be it known that I, Daniel Rubin, a citizen of the United States of America, residing in New York city, county of New York, and State of New York, have invented a new, original, and ornamental Design for a Handbag, of which the following is a specification, reference being had to the accompanying drawing, forming part thereof, wherein,

I claim:

The ornamental design for a handbag, substantially as shown.

DANIEL RUBIN.
